UNITED STATES PATENT OFFICE.

FRED A. LARAWAY, OF CLEVELAND, NEW YORK.

DESIGN FOR A DISPLAY-PACKAGE OF PACKING-GASKETS.

57,531.

Specification for Design.

Patented Apr. 12, 1921.

Application filed August 12, 1920. Serial No. 403,174. Term of patent 7 years.

To all whom it may concern:

Be it known that I, FRED A. LARAWAY, a citizen of the United States, residing at Cleveland, in the county of Oswego and State of New York, have invented a new, original, and ornamental Design for a Display-Package of Packing-Gaskets, of which the following is a specification, reference being had to the accompanying drawing, forming part thereof.

The figure is a face view of the display package, showing my new design.

I claim:

The ornamental design for a display package of packing gaskets, as shown.

FRED A. LARAWAY.
